CUTLERY CLEANING DEVICE

Filed Dec. 12, 1928

Harry Williams

INVENTOR

ATTORNEY

UNITED STATES PATENT OFFICE

HARRY WILLIAMS, OF VANCOUVER, BRITISH COLUMBIA, CANADA

CUTLERY-CLEANING DEVICE

Application filed December 12, 1928. Serial No. 325,474.

The invention relates to improvements in cutlery cleaning devices, as described in the present specification and illustrated in the drawings that form part of the same.

3 The invention consists essentially of the novel arrangement and construction of parts, wherein a cylindrical container is provided with a circular slotted ring adapted to receive within said slots the blades of knives, forks, or the like; the extremities thereof adapted to extend into a circular passage formed between the said ring and wall of the container—said passage adapted to receive and contain a cleaning fluid and shot combined, the machine being so disposed that the aforesaid cylindrical member is driven by suitable friction or tooth gearing while being capable of a hinged movement whereby the said container may be readily lifted from a

20 vertical to a horizontal plane for the purpose of loading and unloading either the cleaning fluid, or the cutlery to be cleaned.

Referring to the drawings:

Figure 1 is an end elevational view showing 25 the container in a horizontal plane for loading.

Figure 2 is an end elevation showing the container in a vertical plane for working with part of the container broken away.

30 Figure 3 is a side view showing the trunnion bearing and driving shaft.

Figure 4 is a detail broken section of packing means.

In the drawings:

35 Like numerals of reference indicate corresponding parts in each figure.

1 represents a suitable housing or frame, having adjustably mounted therein, through suitable bearings 2, a trunnioned shaft 3, on 40 which is provided a short extension member 4 rotatably mounted on which is a cylindrical container 5, said container being provided with a hinged cover 6 and a gearing band 7 cast integral with the container 5 on the outer periphery thereof.

The aforesaid container when rotated by the hinged action of the trunnion 3 to a position as shown in Figure 2, engages through the gearing member 7 with a pinion 8, said pinion being positioned on a driv-

ing shaft 9, which in turn is disposed within suitable bearings 10, said shaft 9 being adapted to receive power from any suitable motor, or other prime mover, directly coupled thereto. Disposed within the framing 55 1 is a cross stay 11 adapted to receive one or more back stops, or rest pieces 12, which take the weight of the container 5 when said container is swung upward to loading or unloading position. The framing member 1 60 may be suitably affixed to any work shop floor by means of bolts or screws at 13. As the container 5 while in working position, as shown in Figure 2, rotates about shaft 4 and is filled with a cleaning fluid, the bearing 14 must be protected from such fluid, and I provide such means by the adaptation shown in Figure 4, wherein the shaft 4 is mounted in a hub 18, said hub extending 65 centrally from inside of casing 5 and provided with a screwed nut 15, a hub cap 17 enclosing the nut 15 and hub 18 is provided, and a suitable packing ring 16 is positioned beneath said hub cap. Within the container 5 aforesaid I provide an annular ring 19 in which are cut a plurality of radially disposed slots 20, sufficient material being removed therefrom to accommodate the blades of knives, or the extremities of any other predetermined articles of cutlery, enabling 70 such articles to project into an annular groove 21 in the manner as indicated by the position of knife 22.

Having now described my invention, the manner in which the same is operated is as follows: The container 5 is swung by means of trunnions 3 and allowed to rest on stops 12, the cover 6 being open, and after the annular space 21 has been filled with suitable 75 cleaning fluid of a predetermined consistency, the ends of the articles to be cleaned are inserted in the slots 20, a predetermined amount of shot being disposed within the annular space 21 at all times, into which the extremities of the articles aforesaid project. The cover 6 is then closed to form contact with a sealing joint of rubber at 24, the container is then swung in a downward direction to insure engagement of gears 7 and 8, 80 and motion is then applied to shaft 9 which 85

rotates within its bearings 10 causing the container 5 to rotate about the shaft extension 4, which as shown in Figure 2, conforms to a horizontal axis. As the container 5 rotates under motion imparted by shaft 9, the liquid and shot within the machine is in turbulent motion, performing a polishing and cleaning action on the extremities of the articles extending into the passage 21.

I am aware, that prior to my invention various machines for cleaning cutlery have been in use, but do not believe attempts have been made to individually retain articles of cutlery to be cleaned, nor has provision been made for ease in loading and unloading, whereby the hands of the operator will be protected in this operation. It will readily be seen that I have invented a device enabling a great number of cutlery articles to be cleaned and polished at one time with dispatch and efficiency, also presenting ease of loading and unloading of the articles, and the filling and emptying of the cleaning compound into and out of the device.

What I claim is:

1. In a cutlery cleaning device, the combination of a frame, a trunnioned shaft mounted therein, provided with an extension shaft, a cylindrical container rotatably mounted upon said extension shaft, said container being provided with an annular ring having radially disposed cutlery receiving slots, said ring being so positioned as to provide an annular fluid passage between the ring and container wall adapted to receive the extremities of cutlery when positioned in aforesaid radially disposed slots, the aforesaid fluid passage being adapted to receive a predetermined amount of cleaning fluid in combination with shot, when said container is in its loading position with aforesaid extension shaft in a vertical plane, cover means on said container, and rest means provided on aforesaid frame to retain aforesaid container in loading position.

2. In a cutlery cleaning device, the combination of a frame, a trunnioned shaft mounted therein, provided with an extension shaft, a cylindrical container rotatably mounted upon said extension shaft, said container being provided with an annular ring having radially disposed cutlery receiving slots, said ring being so positioned as to provide an annular fluid passage between the ring and container wall, adapted to receive the extremities of cutlery when positioned in aforesaid radially disposed slots, the aforesaid fluid passage being adapted to receive a predetermined amount of cleaning fluid in combination with shot, sealing cover means on said container, said container having a gear cast integral with the outer periphery thereof, a pinion gear, said first gear

being adapted for engagement with said pinion gear, when aforesaid container is rotated to extend in a vertical plane, and a drive shaft on which said pinion gear is mounted to impart rotary motion to the aforesaid container.

HARRY WILLIAMS.
